FLOWER CARRIER

David Turner, Cedar Rapids, Iowa

Application May 3, 1938, Serial No. 205,727

5 Claims. (Cl. 206—1)

This invention relates to flower carriers and has particular relation to a collapsible basket for such purposes.

The problem of handling flowers, for instance at funerals, is difficult and large masses of flowers must be transported from place to place without crushing or injury. Furthermore, the means for holding and carrying the flowers must be unobtrusive. The carriers should be light and strong.

It is among the objects of my invention to avoid the difficulties of the devices of the prior art and to provide means for meeting the requirements above set forth.

Another object of my invention is to provide a means for holding and transporting flowers which may be collapsed and hidden before and after using.

Another object of my invention is to provide means for carrying more flowers, without crushing, than any other device.

Another object of my invention is to provide a flower carrying means which displays the mass of flowers to good advantage.

Another object of my invention is to provide a very light, serviceable, strong and reliable device of the above character.

Other and further features and objects of the invention will be more apparent to those skilled in the art upon a consideration of the accompanying drawing and following specification, wherein is disclosed a single exemplary embodiment of the invention, with the understanding, however, that such changes may be made therein as fall within the scope of the appended claims, without departing from the spirit of the invention.

In said drawing:

Figure 1 is a view in perspective of the flower carrier as it appears while being loaded with flowers.

Figure 2 is a view in perspective of the flower carrier in open position, and

Figure 3 is a view in perspective of the flower carrier in folded or collapsed position.

Referring now to the drawing:

A device constructed according to a preferred embodiment of my invention includes a bottom supporting plate 10, end rails 11 and 12, and side rails 13 and 14. It contemplates the provision of means for selectively supporting the rails in extended position above the base where the rails may be utilized for restraining and holding the flowers in position with the base supporting the ends of the stems, and means for permitting these

rails to be folded down against the base when they are not in use.

A preferred construction includes the side bars 16 and 17 which are secured to the base 10, and an end frame or panel 18 which includes the rail 11. The end panel 18 is pivotally mounted on a rod 19 which serves also to assist to hold the bars 16 and 17 in position on the base 10. The end panel 18 is preferably provided with a hand-hold opening 21. The side rails 13 and 14 are pivotally engaged to the upper edge of the panel 18 by means of a rod 22.

Straps or braces 23 and 24 are provided at the opposite end of the base 10 from the plate 18 and these straps are pivotally engaged to the base by means of a through rod 30. They are pivotally engaged to intermediate portions of the rails 13 and 14 by means of pivot pins 26 and 27 and are preferably engaged so that they are parallel to the plane of end panel 18. It may be readily understood by reference to the drawing that the rails 13 and 14 may be raised and lowered on the parallel lever arms afforded by the end panel 18 and the pair of straps 23 and 24.

In order to support and brace the rails 13 and 14 and the end panel 18 in extended position, and in order to support the flowers at the left end of the carrier, I provide a swinging end panel 28 which is pivotally engaged on a through rod 29 passing through the free ends of the rails 13 and 14, and this end panel may swing on the pivot 29. When the carrier is in the raised or extended position, a latch 31 engages on a catch 32 to hold the plate 28 in extended position and thus to hold the rails and end panel 18 in extended position. When it is desired to fold the carrier the latch is released by pulling on the knob 33 of latch 31, and the end panel 28 slides to the right to permit the end panel 18 and straps 23 and 24 to be folded down against the base.

I preferably provide guides for the free end of the end panel 28 such as the slots 34 and 36, and a rod 37 projects through the sides of end panel 28 and into these grooves so that the free end of the end panel 28 is guided by the grooves to prevent it from moving upwardly when the carrier is in the folded position.

A carrier constructed according to my invention is light and strong and provides an adequate support for the flowers. The ends of the carrier slope outwardly to permit fanning out the flowers so that the buds and flowers will not be crushed or injured. When the carrier is filled with flowers it is quite unobtrusive, and when the flowers have been removed the carrier may be folded

and placed out of the way where it is not readily seen. The carrier is quite flat when folded and thus occupies but a very small space. It is strong and reliable.

- 5 6 Although I have described a specific embodiment of my invention, it is apparent that modifications may be made by those skilled in the art. Such modifications may be made without departing from the spirit and scope of my invention 10 as set forth in the appended claims.

10 11 I claim as my invention:

- 11 12 1. A flower carrier including a base, an end panel swingable on the base, side rails pivotally engaged to the free end of the end panel, other 15 spacing members pivotally engaged to the base and to the side rails in a plane parallel with the end member, a second end member pivotally engaged to the side rails, and means on this second end member for detachably engaging it to the 20 base at an angle thereto and at an angle to the spacing members and the first mentioned end panel to provide for bracing said members.
- 20 21 2. In a flower carrier, a base for supporting the ends of the stems of the flowers, means for 25 supporting the flowers including side rails, other means for supporting the side rails including an end panel and including also other members pivotally engaged to the base and to the side rails in a plane parallel to the end panel, and a 30 second end member also pivotally engaged to the rails and having means for locking it on the base at an angle to the first mentioned end panel to act as a brace to hold the rails in extended position.
- 30 31 3. In a flower carrier, a base having side bars, an end panel pivotally engaged to the side bars at one end thereof, a pair of straps also pivotally engaged to the side bars at the opposite ends

thereof, side rails pivotally engaged to the end panel and to the free ends of the straps for swinging movement up and down so that the side rails are always parallel to the base, and a brace for holding the side rails in extended position and for supporting the stems of the flowers at one end of the carrier, the brace being in the form of a second end panel pivotally connected at one end with the side rails, and having means thereon for latching it with respect to the base to hold the carrier in extended position and also having means for slidably engaging the second end panel with the side bars.

5 6 4. In a folding crate, a base member having side bars, a pair of side rails somewhat longer than the side bars, a pair of end panels pivotally connected at their upper ends to the ends of the side rails, the lower end of one panel being pivotally connected to the side bars at one end thereof, a pair of straps pivotally connected to the side bars at the other end and to the side rails so as to be parallel with the last mentioned panel, the lower end of the other panel having means slidably engaged with the side bars, and latch means on that panel and near the adjacent end of the base for fastening the crate in extended position.

10 11 5. In a flower carrier, a base, an end panel pivoted for swinging movement on the base, rails pivotally attached to the end panel, a second 15 panel pivotally attached to the rails and pivotally and slidably connected to the base, and latching means for fixedly engaging the second end panel with the base at an angle to the first mentioned end panel to hold the rails and end members in 20 extended position to form a flower carrier.

25 30 35 DAVID TURNER.
